J.H. MORSE.

Permutation Lock.

No 91,359

Patented Jun. 15, 1869.

United States Patent Office.

JOHN H. MORSE, OF PEORIA, ILLINOIS, ASSIGNOR TO HIMSELF
AND HENRY W. WELLS, OF SAME PLACE.

Letters Patent No. 91,359, dated June 15, 1869; antedated May 28, 1869.

IMPROVEMENT IN PERMUTATION-LOCKS.

The Schedule referred to in these Letters Patent and making part of the same.

To all whom it may concern:

Be it known that I, JOHN H. MORSE, of Peoria, county of Peoria, and State of Illinois, have invented a new and useful Improvement in Safe-Locks; and I do hereby declare the following to be a full and exact description of the same, reference being had to the accompanying drawings, and to the letters of reference marked thereon.

Figure 1 is a perspective view of back of lock, with the back-plate removed.

Figure 2 is a sectional view of said lock.

Figure 3 represents the changeable wheel A, with its rim L.

Figure 4 represents a sectional view of rim L of wheel A.

Figure 5, sectional views of the nut or core B, with movable pin i.

Figure 6, lever J.

Figure 7, an edge view of same.

Figure 8, the adjustable nut D, and sectional view of same.

Figure 9, dial C, showing the unequal cuts and spaces.

My improvement consists in providing the inner end of spindle O, that passes through the door of a safe or vault, with a changeable wheel, A, for the purpose of disconnecting the lug-bar N, and the slotted tumblers or wheels E F G, in a safe-lock.

Also, in placing a friction-wheel, h, on rim L of wheel A, and in placing the lever J in such a position that the friction-wheel h coming in contact with it, (the bolt R R being attached to said lever by the stud s, this stud s sliding in the slot x in lever J,) the bolt R R will be turned into position shown by fig. 1.

In the present position of lever J, the wheel A may be revolved, and the friction-wheel h not come in contact with it; but if the bolt R R is thrown up, as shown in red dotted lines, fig. 1, the friction-wheel h, in passing around, will strike the lever J, (see dotted line, fig. 1,) and force the bolt back again into position shown.

The wheel A consists of three parts: the body, the nut or core B, and the rim L.

The nut B, figs. 2 and 5, is secured upon the spindle O at f. (See fig. 2.)

On this nut B the wheel A revolves, fig. 3, the nut B forming its core.

Through this nut B or core a number of holes, c c, are drilled. (See fig. 5.) In the wheel A one hole is drilled, through which passes the screw m, (see figs. 1 and 3,) into one of the holes in the core B, securing the wheel A and core B together.

The wheel A has a rim, L. (See fig. 3.) In the outer edge of it a slot, e, is cut, and nearly opposite, on the face of said rim, the friction-wheel h is secured by a screw, upon which it revolves, figs. 1 and 3.

The body of spindle O is formed thus: Beginning at g, (see fig. 2, dotted lines,) the spindle is about seven-eighths of an inch in diameter; running toward the end l, it is straight for one-quarter of an inch, to o; then an offset with a receding cut, forming a sharp cutting-edge; then tapers one-quarter of an inch, to s; then straight one-quarter of an inch, to o; then another receding cut, and so on, until three or four of these receding cutting-edges o o o are formed (See fig. 2.)

When an attempt to drive in the spindle O is made, these cutting-edges o o o will cut into the soft iron of the safe-door, and close it around the taper part of spindle at s s s, and prevent the said spindle from being driven in or wedged in the door.

To change the wheel A, or set it on some other figure on the dial, turn the dial or knob C until the slot e in rim L, (see fig. 1,) comes directly under the lug n, with its rubber-tired friction-wheel a on lug-bar N. (See figs. 1 and 2.)

Now take the screw m half way out, hold the wheel A securely with the fingers of the left hand, turn the dial C with the right hand, until the figure selected to set it on is noted by the dial C. Put in the screw m, and the point of said screw will enter one of the holes c c in core B, and secure them together. The position of the slot e will now be noted by the dial C at the cut, t, on rim H. (See fig. 9.)

The working of the changeable wheel A is as follows:

The friction-wheel a, with its rubber tire, runs upon the rim L of wheel A, (see fig. 1,) keeping the lug p (see fig. 1) on lug-bar N, from coming in contact with slotted wheels E F G, except when the slot e in rim L is passing the rubber-tired friction-wheel a. This prevents the "mapping out" of slotted wheels E F G, and finding the slots k. (See fig. 1.)

The rubber on friction-wheel a prevents sound or noise as the wheel A is revolved, and the slot e passes the wheel a.

In working the lock, much depends upon knowing the position of slot e in rim L of wheel A.

The bolt R R is withdrawn by the lug n, with its rubber-tired friction-wheel a, dropping into said slot e, by turning the dial C, (the slotted wheels E F G being in position to receive the lug p,) (see fig. 1,) and the operator, not knowing the position of slot e, in turning the dial C, in an attempt to find its position, may withdraw the bolt R, and bring the friction-wheel h, on rim L of wheel A, against the lever J, and force the bolt R back again into position, or lock it.

To adjust the spindle O to doors not of the same thickness, take out the screw d, and take off the cap, D. (See figs. 1 and 8.) And the said spindle may be lengthened or shortened by holding the wheel A in the fingers of the left hand, and screwing up or un-

screwing the spindle O, as may be required. Put on the cap, D, and secure it to the core B with the screw d.

The cap, D, with its screw d, is used to hold the wheel A securely on the spindle O, and prevent its unscrewing from the core B, thereby changing the position of the dial C and changeable wheel A, or withdrawing the spindle, and leaving a hole in the door.

The dial C is laid off into unequal cuts and spaces, for preventing the working out of the combination on which the lock may be locked with a "michrometer," or other machine which burglars use.

The hand and eye will work to cuts and spaces on the dial C, without regard to their irregularity, while a machine with teeth and pinions will not.

Claims.

What I claim as my invention, and desire to secure by Letters Patent, is—

1. The changeable wheel A, with its rim L, core B, and screw m, in combination with the rubber-tired friction-wheel a, or lug n, all arranged substantially as and for the purposes described.

2. The friction - wheel h, in combination with the crooked lever J and bolt R, arranged substantially as and for the purpose described.

JOHN H. MORSE.
